UNITED STATES PATENT OFFICE.

WILLIAM F. VON BARTHELD, OF NEW YORK, N. Y.

RAILWAY-RAIL.

1,185,739.

Specification of Letters Patent.

Patented June 6, 1916.

Application filed March 28, 1916. Serial No. 87,815.

To all whom it may concern:

Be it known that I, WILLIAM F. VON BARTHELD, a citizen of the United States, residing at New York city, in the county of 5 New York, State of New York, have invented certain new and useful Improvements in Railway-Rails; and I do hereby declare the following to be a full, clear, and exact description of the invention, such as will enable others skilled in the art to which it 10 appertains to make and use the same.

This invention relates to improvements in railway rails, and particularly to street railway rails.

15 One object of the invention is to provide a street railway rail which can be quickly and easily repaired, without the necessity of digging up the adjacent portions of the street paving.

20 Another object is to provide a street railway rail which has a removable tread member, and means for securing the tread member to the body of the rail so constructed and arranged that the flange of the car 25 wheel will engage with the heads of the bolts and have a tendency to force the fastening means back into normal position should they become loosened.

Other objects and advantages will be apparent from the following description when 30 taken in connection with the accompanying drawing.

In the drawing: Figure 1 is a side elevation of a rail made in accordance with my 35 invention; Fig. 2 is a top plan view of a pair of rails constructed in accordance with my invention; Fig. 3 is an enlarged transverse section on the line 3—3 of Fig. 2; Fig. 4 is an enlarged longitudinal sectional view on 40 the line 4—4 of Fig. 2.

Referring particularly to the accompanying drawing, the rail includes a base portion 10, a vertical web portion 11, a head portion 12, and a removable tread portion 13. On 45 the upper face of the head portion 12 there are formed two longitudinally extending grooves 14 into which are received the longitudinally extending ribs 15 formed on the under face of the tread portion 13. This 50 tread portion has the longitudinal channel

16 in its upper face as is usual in the U-type of rails, in street railways. Formed in the center of the head portion 12 there is a line of threaded sockets 17 which align with vertical openings 18 formed through the tread portion 13, said openings having their upper portions countersunk to receive the heads of the bolts 19 which are passed therethrough and secured into the sockets 17.

The bolts which are disposed through the right hand rail are provided with right hand threads while those passed through the left hand rail are provided with left hand threads, whereby when any of the bolts work upwardly into the channels 16, they will be engaged by the flanges of the car wheels and turn thereby so as to be driven downwardly and held in such position. It will be noted that this is effected by having the heads of the bolts positioned so that they lie closer to the outside of the slots or channels 16 and that this enables the inner parts of the heads to be engaged by the flanges of the wheels, the outer parts of the heads being protected from such engagement by reason of the running of such flanges in the ordinary construction of wheels. When applying the bolts, graphite is placed in the openings and sockets so that there will be no tendency toward rusting, thus more easily permitting 80 of the removal of the bolts when it is desired to take off the tread portion for repairs, or for replacing the same with a tread portion.

It will be noted that the base or body portions of the rails and the removable tread portions are so arranged that the joints between the former are disposed at points intermediate the ends of the latter. This provides a smooth surface and eliminates the bump or click as the car wheels pass over 90 the joints.

What is claimed is:

A tramway rail comprising a body portion in the form of an I beam, the upper face of which is formed with longitudinally 95 extending parallel grooves and an intermediate longitudinal series of threaded sockets, a removable tread member having longitudinal parallel ribs on the lower face thereof for reception within the said grooves and an 100

intermediate series of vertical openings registering with the sockets of the body member and extending upwardly through the bottom of the channel of said tread member, and
5 bolts disposed through the openings and into the sockets, the heads of the bolts being countersunk in the bottom of said channel.

Copies of this patent may be obtained for five cents each, by addressing the "Commissioner of Patents,
Washington, D. C."

In testimony whereof, I affix my signature, in the presence of two witnesses.

WILLIAM F. von BARTHELD.
